TRAFFIC CONTROL SYSTEM

Benjamin Cooper, Jersey City, N. J.

Application February 21, 1940, Serial No. 320,020

36 Claims. (Cl. 177—337)

This invention relates to traffic control systems.

In highways, bridges, tunnels, and the like arteries for vehicular traffic, particularly where there is only one lane for each direction of vehicular travel, any obstruction to the flow of traffic, or slowing down of traffic below a predetermined speed, as may be caused by a vehicle stalling in the roadway, will result in blocking traffic and delay. If the normal movement of traffic is not restored quickly, a serious tie-up may follow. In highway tunnels, where traffic is not visible from the outside, a group of officers are usually maintained to continually patrol the highway within the tunnel and report to a traffic supervisor any obstruction in the lane or speeding violations, so that the necessary action may be immediately taken to clear the highway or apprehend the violators. These methods of traffic supervision are expensive and relatively slow. It is an object of this invention therefore to provide an automatic traffic control system which will automatically detect an interruption in the flow of traffic anywhere along the highway, and operate a warning signal located outside of the tunnel or at any point remote from the roadway, to indicate that traffic has been held up.

It is a further object of this invention to provide, in a traffic control system of the character described, automatic means for determining the approximate location of the obstruction on the highway and indicating said location on a supervisory panel located at any convenient point, remote from the highway.

It is still a further object of this invention to provide in a traffic supervisory system of the character described, means for regulating traffic lights disposed along the highway so that when traffic is held up, all the lights before the obstructed area turn red, whereas the lights after the obstruction are green. Thus, vehicles moving toward the obstructed area are stopped, preventing a traffic jam, whereas vehicles moving away from said area are permitted to continue.

In traffic lanes, curves become points of danger. When vehicles traversing these lanes pass these points at greater speeds than is ordinarily safe, the possibility of accidents resulting is great. It is therefore a still further object of this invention to provide means to caution drivers when they are exceeding safe speeds over a section of a lane of a highway, and to further provide means to indicate on a remote panel

in which section of a lane vehicles are being driven at excessive speed.

Still another object of this invention is to provide a traffic supervisory system of the character described which shall be relatively inexpensive to manufacture, positive in operation, and yet practical and efficient to a high degree in use.

Other objects of this invention will in part be obvious and in part be hereinafter pointed out.

The invention accordingly consists in features of construction, combination of elements, and arrangement of parts which will be exemplified in the construction hereinafter described, and of which the scope of application will be indicated in the following claims.

In the accompanying drawings:

Fig. 1 illustrates a schematic drawing of the traffic control circuit embodying the invention;

Fig. 2 is a front view of a differential counter used in connection with said circuit; and

Fig. 3 represents a supervisory panel upon which the warning signal and indicating devices may be located.

Referring now to the drawings, the traffic control system embodying the invention comprises a plurality of vehicle treadles such as 11, 12, 13, 14 and 15, Fig. 1, disposed at spaced intervals along a lane of a highway, traversely thereof. The treadles may be of any suitable type adapted to close a switch when actuated by a vehicle passing thereover, and may comprise pairs of top and bottom contact strips such as 11a—11b; 12a—12b; etc., normally spaced apart but adapted to be pressed together for closing an electrical circuit when the wheels of a vehicle pass over the treadle. The sections of highway bounded by successive treadles are designated in the drawings as sections A, B, C, and D; section A being located between treadles 11 and 12, section B lying between treadles 12 and 13, etc. Said highway sections have associated therewith similar differential counters A10, B10, C10 and D10, respectively, one of which is shown in detail in Fig. 2 of the drawings.

Referring now to Fig. 2, each counter comprises a vertical mounting panel 20 having rotatably mounted thereon and disposed in the same vertical plane two pairs of similar, vertically aligned sprocket wheels 21, 23 and 22, 24. Connecting wheels 21 and 23 is an endless link chain 25, the links thereof meshing with the sprockets of said wheels. The wheels 22 and 24 are similarly connected by an endless chain 26.

Floatingly supported on end between the chains

25 and 26 is a sprocket wheel 27, the sprockets thereof being engaged by the links of said chains. The wheel 27 is journaled as at 27a on a vertical rod 28. Said rod 28 is movable in a vertical direction and is slidably received within guide blocks 29 and 30, attached to the plate 20. For purposes hereinafter appearing, the rod 28 has attached to its bottom end an insulating stud 28a.

When wheel 21 is rotated in a counter-clockwise direction, looking at Fig. 2 of the drawings, chain 25 moves wheel 27 upwardly and raises rod 28. When wheel 22 is rotated counter-clockwise wheel 27 and rod 28 are moved downwardly.

Means is provided to move the rod 28 of the corresponding differential counter upwardly a predetermined distance each time a vehicle axle enter a particular section of highway, and to move said rod downwardly an equal distance each time a vehicle leaves said highway section, so that the vertical position of rod 28 will continuously indicate the number of vehicle axles within said highway section.

To this end, there is mounted on wall 20, above the wheel 21, a horizontal electromagnet 31 having a U-shaped core 32 comprising parallel upper and lower horizontal legs 33 and 34. Surrounding leg 34 is a coil 35. Pivoted to the end of leg 33 and extending downwardly therefrom adjacent the leg 34 is an armature 36 normally urged in a clockwise direction against a stop 38 by a coil tension spring 37. Pivoted to the bottom end of armature 36, as at 39a, is a pawl 39. Rigidly attached to the sprocket wheel 21 and concentric therewith is a ratchet wheel 40 contacted by the pawl 39. A coil tension spring 41, connected between said pawl 39 and the armature 36, tensions said pawl into engagement with the ratchet 40.

Each time the coil 35 is energized the armature 36 is attracted counter-clockwise moving the pawl 39 to the right and advancing wheel 21 a predetermined angle in a counter-clockwise direction. Wheel 27 and rod 28 are consequently raised a predetermined distance.

The sprocket wheel 22 is similarly controlled by an electromagnet 42 having a coil 43 and a pawl 44 contacting a ratchet wheel 45 on wheel 22. Ratchet 45 is similar to ratchet 40 so that wheels 21 and 22 are advanced equal angular distances for each actuation of their respective electromagnet. Hence each energization of the coil 43 lowers rod 28 by an amount equal to the distance said rod is raised when coil 35 is energized.

The coils 35 corresponding to the counters A10, B10, C10 and D10 are designated as A35, B35, C35 and D35, respectively; and the coils 43 of said counters are designated as A43, B43, C43, respectively. Referring to Fig. 1, one end of the coils A35, B35, C35 and D35 are connected to the negative power supply through the treadle switches 11, 12, 13 and 14, respectively, the other of said coils being connected together and to the positive power supply. The coils A43, B43, C43 and D43 have one end thereof connected to the negative power supply through the treadles 12, 13, 14 and 15, respectively, whereas their other ends are connected directly to the positive power supply.

It is seen, therefore, that each time an axle of a vehicle moving along the highway traverses a treadle switch and moves from one section into a succeeding section, the coil A43, B43, C43 or

70 D43 corresponding to said section from which the vehicle is exiting, is energized, for lowering the respective rod 28 and indicating that a vehicle axle has left said section. Furthermore, the coil A35, B35, C35 or D35, corresponding to the succeeding highway section into which the vehicle is entering is simultaneously energized for raising the rod 28 corresponding to said succeeding section, and indicating that an additional axle has entered said section.

The counters A10, B10, C10 and D10 may be mounted together on the back side of a supervisory control panel such as panel 46, of Fig. 3. Said panel is formed with a plurality of slots 47 through which the rods 28 are visible. Said rods 28 may be provided with an indicating mark such as the colored section 48, by means of which the vertical position of the rods can be determined by glancing at the front of the panel. Furthermore, a scale calibrated in units of vehicle axles may be mounted on the front of said panel adjacent to slots 47 so that an observer can immediately determine the density of traffic in any section.

There are also mounted on the supervisory panel 46, incandescent lamps A59, B59 and C59, corresponding respectively to the highway sections A, B and C. Means is provided to illuminate the lamps corresponding to the various sections when the flow of traffic in said sections is obstructed by a stalled car in the roadway.

To this end the counters A10, B10, C10 and D10 are provided with contact arms A50, B50, C50 and D50, mounted on the respective panels 20 beneath the rods 28. Arms A50 and C50 are connected to negative power supply and the arms B50 and D50 are connected to the positive power supply, Fig. 1. Said contact arms are adapted to be contacted and moved downwardly by the insulating studs 28a when the respective rods 28 are in bottom position, corresponding to the condition that there are no vehicles in the respective highway section.

Arm A50 is normally open but is moved into engagement with a fixed contact A51 when the corresponding rod 28 is raised by the presence of one or more vehicle axles in section A.

The arm B50 normally engages a fixed contact B52 but is moved away therefrom and into engagement with the fixed contact B51 when there are vehicle axles in section B.

The arm C50 similarly engages a fixed contact C52 but is moved into engagement with the fixed contact C51 when the rod 28 of counter C10 is raised from its bottom position.

The arm D50 normally engages fixed contact D52 when the highway section D is vacant, but is moved away therefrom when the corresponding rod 28 is raised by the presence of vehicle axles in section D.

There are further provided three similar relays A53, B53 and C53, corresponding respectively to the sections A, B and C. Said relays may be of any suitable time delayed type, constructed so that the respective contact arms are not actuated until the coil has been energized for a predetermined time interval. If the coil is energized and then de-energized before the predetermined time interval has elapsed, the relay becomes reset and the coil must be re-energized for the complete time interval before the contact arms are actuated. Relays of this type are old in the art.

Relay A53 has an actuating coil A54 and controls two normally open contact arms A55 and A57 which move into engagement with the fixed

contacts A56 and A58 when said relay is actuated. Relay B53 has a coil B54 and also controls two normally open contact arms B55 and B57 which engage the fixed contacts B56 and B58 when said relay is energized. Similarly relay C53 has a coil C54 and moves normally open contact arms C55 and C57 into engagement with the contact C56 and C58 when said relay is energized.

The coils A54, B54 and C54 have one end thereof connected by wires A60, B60 and C60 to fixed contact A51, B51 and C51, respectively, of the corresponding differential counters. The other ends of said coils are connected by wires A61, B61 and C61 to the fixed contacts B52, C52 and D52, respectively, of the differential counter of the next succeeding highway section. The contact arms A55, A57, B55, B57, and C55, C57 are connected to the negative power supply.

The indicating lamps A59, B59 and C59 have one terminal thereof connected to the positive power supply and have their other terminals connected to the fixed contacts A58 and C58, respectively.

When a vehicle axle enters a highway section such as B, the corresponding rod 28 is raised permitting contact arm B50 to engage fixed contact B51. If there are no vehicle axles in the next succeeding section the arm C50 is in engagement with the contact C52, as heretofore described. A circuit is thus completed through coil B54 of relay B53, traceable from positive power supply, arm B50, contact B51, wire B60, coil B54, wire B61, contact C52, contact C50, to negative power supply. The time delay of relay B53 is pre-set for a time interval slightly in excess of the normal time required for a vehicle to traverse the section B. Thus, if the vehicle continues along at the normal rate of speed it will enter section C and actuate counter C10 for raising the rod 28 before relay B53 has had sufficient time to become actuated. The contact arm C50 will thereupon move out of engagement with the contact C52 and open the above mentioned circuit for the relay B53. The time delay of said relay is thereupon reset to zero pending reactivation by a subsequent vehicle axle.

However, if a vehicle should remain in section B longer than the time delay of B53, as for example because of a vehicle breakdown or accident, contact arm B50 will remain in engagement with the arm B51. The vehicles following the stalled car would have to stop since the lane is blocked. However, the vehicles ahead of the obstructed section can continue to move until there are no vehicles in the section C. Thus, the contact arm C50 will move into engagement with the contact C52 and will remain engaged therewith until the obstruction has been cleared for permitting vehicles to move again over the highway lane. The relay B53 is thereupon energized as heretofore described, and will remain energized until the flow of traffic is restored. After the necessary time delay interval of relay B53 has elapsed, the contact arms B55, B57 will move into engagement with the fixed contacts B56, B58. The lamp B59 is thereupon energized through a circuit from negative power supply, arm B51, contact B58, lamp B59, to positive power supply.

Since the lamp B59 is located on the supervisory control panel, when lamp B59 becomes illuminated the traffic supervisory personnel are immediately informed that the section B of the highway is blocked and the necessary steps may be taken to clear the obstructed section.

Means is also provided to actuate a warning

signal, herein illustrated as a bell W, when any of the indicating lamps are illuminated, to immediately attract the attention of the supervisory personnel when the highway becomes blocked.

5 To this end there are provided three secondary relays A63, B63 and C63 corresponding to the relays A53, B53 and C53, respectively.

Relay A63 has an actuating coil A62 and controls two contact arms A64, A66. The arm A64 is normally open whereas arm A66 normally engages a fixed contact A70. When said relay A63 is energized arm A64 is moved into engagement with a fixed contact A67 and arm A66 is moved into engagement with a fixed contact A69.

15 The relay B63 has an actuating coil B62 and controls three switch arms B64, B65 and B66 of which the arms B64 and B65 are normally open whereas arm B66 normally engages fixed contact B70. When said relay B63 is energized the arms B64 and B65 are moved into engagement with fixed contacts B67 and B68, and arm B66 is moved out of engagement with contact B70 and into engagement with contact B69.

20 The relay C63 similarly has a coil C62 and controls three switch arms C64, C65 and C66 of which arms C64 and C65 are normally open whereas arm C66 normally engages the fixed contact C70. When relay C63 is energized the arms C64, C65 and C66 move into engagement with the fixed contacts C67, C68 and C69, respectively.

25 Coils A62, B62 and C62 have one end thereof connected to the positive power supply and their other ends are connected by wires A71, B71 and C71 to the fixed contacts A56, B56 and C56, respectively, of the relays A53, B53 and C53. It is seen that when any of the time delayed relays, such as relay B53, is actuated the corresponding secondary relay, such as relay B63, is energized through a circuit from negative power supply, arm B55, contact B56, wire B71, coil B62, to positive power supply.

30 One end of the actuating coil W1 of bell W, is connected to positive power supply and the other end of said coil is connected by wires A72, B72 and C72 to the fixed contacts A67, B67 and C67, respectively. It is seen that when any secondary relay A63, B63 and C63 is energized the warning bell W is actuated through a circuit from positive power supply, coil W1, switch arm A64, B64 or C64 to negative power supply. Thus, when any indicating lamp A59, B59 or C59 is illuminated, the warning bell W is simultaneously energized, for attracting attention to the fact that the highway is blocked.

35 Disposed along the highway are traffic signal lights A75, B75 and C75, preferably located adjacent the corresponding treadles 11, 12 and 13, respectively. Said signals comprise red lights A76, B76 and C76 and green lights A77, B77 and C77, respectively.

40 The lamps A76 and A77 have one end thereof connected together and to positive power supply. The other end of lamp A76 is connected by wire A78 to the fixed contact A69 and the other terminal of lamp A77 is connected to the fixed contact A70 by wire A79.

45 Similarly, the lamps B76 and B77 have one end thereof connected by wires B78 and B79 to the fixed contacts B69 and B70, respectively, whereas the other end of said lamps are connected together and to positive power supply. The lamps C76 and C77 also have one end connected to positive power supply whereas their other ends are connected by wires C78 and C79 to the fixed contacts C69 and C70, respectively.

It will now be understood that the green lights A71, B71 and C71 are normally illuminated, the circuit for light A71 being traceable from negative power supply, arm A68, contact A70, wire A79, light A71, to positive power supply. Similarly, the circuits for lights B71, C71 involve switches B68, B70 and C68, C70, respectively.

However, when any secondary relay becomes energized, as heretofore described, by reason of the obstruction of traffic in the corresponding highway section, the corresponding arm A68, B68 or C68 is moved out of engagement with the respective contact A70, B70 or C70, and into engagement with the contacts A69, B69 or C69. Thus, the corresponding green traffic light is extinguished, and the red light is stopped under the direction of said red light, preventing a traffic jam in said section.

Means is also provided to change the green lights of all sections located before the obstructed section to red. To this end the fixed contact C68 is connected by wires C80 and B71 to the coil B62 and contact B68 is connected by wire B80 and A71 to the coil A62. When the secondary relay C63 is energized a circuit is completed for energization of coil B62 traceable from negative power supply, contact arm C65, contact C68, wire C80, wire B71, coil B62, to positive power supply. Similarly, when relay B63 becomes energized, a circuit for energization of coil A62 is completed from negative power supply, contact arm B65, contact B68, wire B80, wire A71, coil A62 to positive power supply. It is thus seen that when any secondary relay is energized all the secondary relays prior to said energized relay will be successively actuated. Consequently all the green lights located before the obstructed section will be changed to red, whereas the traffic lights of succeeding highway remain green.

It is understood that as many highway sections as desired may be included in the supervisory system described herein. Each additional highway section requires an additional treadle, differential counter, time delayed relay, secondary relay and traffic lights. Said additional equipment is connected into the circuit in a manner similar to the section B of Fig. 1.

It will also be understood that instead of using a single contact treadle as shown in Fig. 1, a uni-directional multi-contact treadle may be used such as is described in my co-pending application Serial No. 34,525 filed August 3, 1935. In such case the counter F of said co-pending application is replaced by a relay controlling an additional normally open switch replacing the treadle of this application. Thus a vehicle traversing the highway in one direction will close said additional switch and actuate the differential counter. A vehicle traversing the highway in the opposite direction will not energize said relay and will produce no effect on the supervisory system.

The use of uni-directional treadles in the circuit disclosed in this application is sometimes necessary in highways where vehicle drivers may traverse the dividing line between lanes carrying traffic in opposite directions, and actuate a treadle in the opposite lane. With the unidirectional treadle this will have no effect on the operation of the supervisory system of said opposite lane.

Means is also provided to caution operators driving vehicles along the lane at an excessive speed, and also to indicate on the control panel where the speeding is taking place. To accom-

plish this purpose there are provided signals B81, C81 etc., associated with the sections B, C etc. Said signal may be in the form of a caution light or any other suitable warning device.

5 There is no caution light in the front section A. On the control panel are indicating devices B98, C98 etc. located adjacent the differential counter B10, C10 etc., there being none adjacent counter A10.

10 Associated with the differential counters A10, B10, C10 etc., are switch arms A110, B110 and C110 etc. respectively. These switch arms are connected by wires A112, B112, C112 etc. to the treadle switch contacts 11b, 12b, 13b etc., respectively. The switch arms A110, B110, and C110 etc. are adapted to be held by the rods A28 of differential counters A10, B10, C10 etc. in engagement with fixed contacts A111, B111 and C111 etc. until the rods are raised by passage of at least two cars into the sections associated with said respective counters.

15 Associated with the counters A10, B10 and C10 etc. are relays A83, B83, C83 etc. Said relays are provided with coils A84, B84, C84 etc. respectively, connected to the fixed contacts A111, B111, C111 etc. The relays A83, B83, C83 etc. are adapted to move normally open switch arms A85, B85, C85 etc. into engagement with fixed contacts A86, B86, C86 etc. respectively. The switch arms A85, B85 and C85 etc., are connected to the minus power supply.

20 Associated with the differential counters A10, B10 and C10 etc., are fast closing, slow opening time delay relays A87, B87, C87 etc. respectively, provided with coils A88, B88, C88 etc., connected to the fixed contacts A86, B86 and C86 etc. respectively, at one side, and each connected to the plus power supply at the other side. The relays A87, B87, C87 etc. are adapted to move switch arms A89, B89 and C89 etc. which are normally in engagement with fixed contacts A90, B90 and C90 etc. respectively, out of engagement with respect to said fixed contacts. Said switch arms are connected to the plus power supply. The relays A87, B87 and C87 are also adapted to move normally open switch arms A91, B91 and C91 etc., into engagement with fixed contacts A92, B92 and C92 etc. respectively. The coils A84, B84 and C84 etc. of the relays A83, B83 and C83 etc. respectively are connected by wires A113, B113 and C113 etc. to the fixed contacts A90, B90 and C90 etc. respectively.

25 Associated with the differential counters A10, B10 and C10 etc. are relays A93, B93, C93 etc. having coils A94, B94 and C94 etc. respectively. Said coils are connected by wires A114, B114, C114 etc. to the treadle switch contacts 12b, 13b and 14b etc. respectively, of the switches 12, 13, 14 etc. The other sides of the coils A94, B94, C94 are connected by wires A115, B115, C115 etc., to the fixed contacts A92, B92 and C92 etc. respectively. The relays A93, B93, C93 are adapted to move normally open switch arms A95, B95, C95 etc., which are connected to the minus power supply, into engagement with fixed contacts A96, B96, C96 etc. respectively.

30 The fixed contacts A96, B96 and C96 are connected to warning signal devices A81, B81, C81 etc. disposed in the sections B, C, D etc., said 35 warning signals being connected to the plus power supply. The relays A93, B93, C93 etc. are also adapted to move normally open switch arms A97, B97, C97 etc. which are connected to the minus power supply, into engagement with fixed contacts A98, B98 and C98 etc. Said fixed con-

tacts are connected to indicating devices B89, C89, D89 etc. which are preferably mounted on the control panel 56 and located adjacent the differential counters B10, C10, D10 etc. respectively. The relays A83, B83, C83 etc. are quick closing, slow opening time delay relays, for the purpose hereinafter appearing.

When a vehicle is the first to enter a given section such as A, relay A83 is energized, receiving current from the negative power supply through treadle 11, movable contact arm A110, fixed contact A111, coil A84, fixed contact A80, movable contact arm A89 to the positive of the power supply.

Energization of relay A83 moves movable contact arm A85 into contact with fixed contact A86 and completes a circuit from negative power supply to arm A85, contact A86 through coil A88 of relay A87 to positive power supply, thus energizing said relay A87.

Energization of relay A87 starts the timing process for the first vehicle of the group that had entered section A. Contact A89 is moved out of engagement with contact A90, and so prevents relay A83 from being again energized when relay A87 is in holding position. Movable arm A91 is moved into contact with fixed contact A92, providing a circuit through which time delay relay B93 will be energized if relay A87 has not released contact arm A91.

If the vehicle reaches treadle B after the predetermined time of relay A87, he has not exceeded the fixed speed limit, and so relay A93 cannot be actuated. If however he has exceeded the speed limit, relay A83 will be actuated, receiving current from the negative of the power supply through treadle 12, coil A84 of relay A83, fixed contact A92, movable contact A91 to the positive of the power supply.

Energization of relay A83, brings moveable contact arms A85, A91 into contact with fixed contacts A96, A98, and so closes a circuit through the caution light B81, from negative of power supply to contact arm A95, contact A96, light B81 to the positive. This operation also closes a circuit through B99 on the panel 46 from the negative of the power supply to contact arm A97, contact A98, and light B99 to the positive of the power supply.

The same operation takes place in succeeding sections as described above.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein described or shown in the accompanying drawings is to be interpreted as illustrative and not in a limiting sense.

Having thus described my invention, I claim as new and desire to secure by Letters Patent:

1. In an automatic traffic system, a plurality of vehicle actuated switches disposed at spaced intervals along the lane of a highway, dividing said highway into a plurality of sections, an electrically operated warning device, and means controlled by said vehicle actuated switches, and including a circuit for said device and said switches, to energize said warning device when a vehicle traversing the highway passes the entering switch of any section and remains within said section longer than a predetermined period of

time, during which period no vehicles cross the exit switch of said section, and all vehicles which have crossed the exit switch of said section into the succeeding section, have left said succeeding section by passing over the exit switch thereof prior to the beginning of said period, whereby said device indicates that traffic through said first section is obstructed.

2. In a traffic control system, a plurality of vehicle actuated switches disposed at spaced intervals along the lane of a highway, dividing said highway into a plurality of successive sections, a plurality of electrically operated indicating devices, one for each section, and means controlled by said vehicle actuated switches, and including a circuit for said devices and said switches, to operate one of said indicating devices when a vehicle traversing the highway crosses the entering switch of the section corresponding to said device and remains in said section longer than a predetermined period of time after any vehicles which have traversed the exit switch of said section and moved into the succeeding section have left said succeeding section by crossing the exit switch thereof.

3. In a traffic system, a plurality of vehicle actuated switches disposed at spaced intervals along the lane of a highway, dividing said highway into a plurality of successive sections, a plurality of electrically operated indicating devices, one for each section, and means controlled by said vehicle actuated switches, and including a circuit for said devices and said switches, to operate one of said indicating devices when a vehicle traversing the highway crosses the entering switch of the section corresponding to said indicating device and remains in said section longer than a predetermined period of time after any vehicles which have traversed the exit switch of said section and moved into the succeeding section have left said succeeding section by crossing the exit switch thereof, a warning device, and means included in said circuit for actuating said warning device when any of said indicating devices have become actuated.

4. In a traffic supervisory system, a plurality of vehicle actuated treadles disposed at spaced intervals along the lane of a highway, dividing said highway into a plurality of successive sections, a plurality of electrically operated indicating devices, one for each section, and means controlled by said vehicle actuated treadles, and including a circuit for said devices and said treadles to operate one of said devices when a vehicle traversing the highway crosses the entering treadle of the section corresponding to said device and remains in said section longer than a predetermined period of time after any vehicles which have traversed the exit treadle of said section and moved into the succeeding section have left said succeeding section by crossing the exit treadle thereof, "stop" traffic signal means associated with a plurality of said sections, and means included in said circuit to cause the traffic signal means associated with all sections preceding said succeeding section to indicate "stop" when said indicating device is actuated.

5. In a traffic supervisory system, a plurality of vehicle actuated treadles disposed at spaced intervals along the lane of a highway, dividing said highway into a plurality of successive sections, a plurality of electrically operated indicating devices, one for each section, and means controlled by said vehicle actuated treadles, and

including a circuit for said devices and said treadles, to operate one of said devices when a vehicle traversing the highway crosses the entering treadle of the section corresponding to said device and remains in said section longer than a predetermined period of time after any vehicles which have traversed the exit treadle of said section and moved into the succeeding section, have left said succeeding section by crossing the exit treadle thereof, a warning device, means for actuating said warning device when any of said indicating devices have become actuated, "stop" traffic signal means associated with a plurality of said sections, and means included in said circuit to cause the signal means associated with all sections preceding said succeeding sections to indicate "stop" when said indicating device is actuated.

6. In a traffic control system, a plurality of vehicle actuated treadles disposed at spaced intervals along the lane of a highway dividing said highway into a plurality of successive sections, a differential counter for each section, means, including a circuit for said treadles and said counters, controlled by the treadles bounding any section for counting on the corresponding differential counter the vehicle axles within said section at any instant, an electrically operated indicating device for each section, and means controlled by said counters for actuating said indicating device when the counter of the corresponding section indicates that there has been one or more vehicle axles in said section for a predetermined period of time, while during said period there has been no vehicle axles in the next succeeding section.

7. In a traffic control system, a plurality of vehicle actuated treadles disposed at spaced intervals along the lane of a highway dividing the highway into a plurality of successive sections, a differential counter associated with each section, means, including a circuit for said treadles and said counters, controlled by the treadles bounding any section for counting on the corresponding differential counter the vehicle axles within said section at any instant, an electrically operated warning device, means controlled by said counters for actuating said warning device when the counter of any section indicates that there have been one or more vehicle axles in said section for a predetermined period of time while during said period there has been no vehicle axles in the next succeeding section.

8. In combination, a plurality of vehicle actuated treadles, disposed at spaced intervals along the lane of a highway, dividing said highway into a plurality of successive sections, "stop" traffic signal means associated with the plurality of said sections, means, including an electric circuit for said treadles and said signal means, to cause the traffic signal means associated with any section and all preceding sections to indicate "stop" when a vehicle traversing the highway passes the entering treadle of said section and remains in said section longer than a predetermined period of time during which no vehicle passes the exit treadle of said section and all vehicles which have passed the exit treadle of said section into said succeeding section have left said succeeding section by passing over the exit treadle thereof prior to the beginning of said period.

9. In combination with a plurality of vehicle actuated treadles disposed at spaced intervals along the lane of a highway dividing said high-

way into a plurality of successive sections, a plurality of "stop" and "go" traffic signals associated with a plurality of said sections, said signals all being normally set for "go," means, including an electric circuit for said treadles and said signal means, to cause the signal means associated with any section and all preceding sections to indicate "stop" when a vehicle traversing the highway passes the entering treadle of said section and remains in said section longer than a predetermined period of time during which no vehicle passes the exit treadle of said section and all vehicles which have passed the exit treadle of said section into said succeeding section have left said succeeding section by passing over the exit treadle thereof prior to the beginning of said period, means, included in said circuit to also cause the traffic signals associated with all treadles preceding said section to change from "go" to "stop," whereas the signals succeeding said section remain set for "go."

10. In a traffic control system, a plurality of vehicle actuated switches disposed at spaced intervals along the lane of a highway, dividing said highway into a plurality of successive sections, a control panel, a plurality of indicating devices one for each section, mounted thereon, and means controlled by said vehicle actuated switches, and including a circuit for said switches and said devices, to operate one of said devices when a vehicle traversing the highway crosses the entering switch of the section corresponding to said device and remains in said section longer than a predetermined period of time after any vehicles which have traversed the exit switch of said section and moved into the succeeding section have left said succeeding section by crossing the exit switch thereof.

11. In a traffic control system, a plurality of vehicle actuated switches disposed at spaced intervals along the lane of a highway, dividing said highway into a plurality of successive sections, a plurality of electrically operated indicating devices, one for each section, and means controlled by said vehicle actuated switches, and including a circuit for said switches and said indicating devices, to operate one of said indicating devices when a vehicle traversing the highway crosses the entering switch of the section corresponding to said device and remains in said section longer than a predetermined period of time after any vehicles which have traversed the exit switch of said section and moved into the succeeding section have left said succeeding section by crossing the exit switch thereof, all of said indicating devices being located in juxtaposition so that they may all be seen at once.

12. In combination with means, located at spaced points along a traffic lane, and dividing said lane into a series of contiguous zones, and responsive to vehicular movement along said lane, electric means located at a central station controlled by said first means for indicating in which of said zones speed of vehicular traffic is below a predetermined speed.

13. In combination with means, located at spaced points along a traffic lane, and dividing said lane into a series of contiguous zones, and responsive to vehicular movement along said lane, electric means located at a central station controlled by said first means for indicating in which of said zones speed of vehicular traffic is below a predetermined speed, and means to indicate the density of vehicular traffic in any zone along said lane.

14. In combination with means, located at spaced points along a traffic lane, dividing said lane into a series of contiguous zones, and responsive to vehicular movement along said lane, electric means located at a central station, controlled by said first means for indicating in which of said zones speed of vehicular traffic is below a predetermined speed, and electrically controlled traffic signalling means controlled by said vehicle responsive means to signal "go" to traffic in said lane when traffic is moving above said predetermined speed, and to signal "stop" in any zone where speed is reduced to below said predetermined speed and to signal "stop" in all zones back of said last zone.

15. In combination with means, located at spaced points along a traffic lane, dividing said lane into a series of contiguous zones, and responsive to vehicular movement along said lane, electric means located at a central station controlled by said first means for indicating in which of said zones speed of vehicular traffic is below a predetermined speed, and means to indicate the density of vehicular traffic in any zone along said lane, and electrically operated traffic signalling means controlled by said vehicle responsive means to signal "go" to traffic in said lane when traffic is moving above said predetermined speed, and to signal "stop" in any zone where speed is reduced to below said predetermined speed and to signal "stop" in all zones back of said last zone.

16. In combination with means, located at spaced points along a traffic lane, dividing said lane into a series of contiguous zones, and responsive to vehicular movement along said lane, electric means controlled by said first means for indicating if speed of vehicular traffic in any zone along said lane is below a predetermined speed, and means located at a central station and controlled by said first means to indicate in which zone along said lane the traffic has slowed down below said predetermined speed.

17. In combination with means, located at spaced points along a traffic lane, dividing said lane into a series of contiguous zones and responsive to vehicular movement along said lane, electric means controlled by said first means to indicate if vehicular movement in any zone along said lane is above a predetermined speed, and electric means located at a central station controlled by said first means to indicate in which zone along said lane, the traffic has increased above said predetermined speed.

18. In combination with means, located at spaced points along a traffic lane, dividing said lane into a series of contiguous zones, and responsive to vehicular movement along said lane, electric means located at a central station and controlled by said first means for indicating in which zone speed of vehicular traffic along said lane is below a predetermined speed, and electric means located at said station and controlled by said first means to indicate in which zone flow of traffic on said lane is above another higher predetermined speed.

19. In an automatic traffic control system, a plurality of switches disposed at spaced intervals along the lane of a highway, dividing said lane into a series of contiguous sections and adapted to be successively actuated by vehicles passing along said lane, a signalling device associated with each section and means controlled by passage of a vehicle over a section of said lane in less than a predetermined time, to actuate the signalling device associated with a succeeding

section, a remote control panel, and means thereon to concurrently indicate which signalling device has been actuated.

20. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each section, means controlled by the actuation of a differential mechanism of one section to actuate the time delay relay of that section only when

10 the differential mechanism of the next succeeding section is not operated after actuation of the preceding mechanism within the time set on said time delay relay, a "go" signal, normally operative, in each section, a "stop" signal in each 15 section, and means controlled by the time delay relay in a section to extinguish the "go" signal and operate the "stop" signal in said section upon actuation of said time delay relay.

21. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each section, means controlled by the actuation of a differential mechanism of one section to actuate the time delay relay of that section only when

25 the differential mechanism of the next succeeding section is not operated after actuation of the preceding mechanism within the time set on said time delay relay, a "go" signal, normally operative, in each section, a "stop" signal in each 30 section, and means controlled by the time delay relay in a section to extinguish the "go" signal and operate the "stop" signal in said section upon actuation of said time delay relay.

35 22. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each section, means controlled by the actuation of a differential mechanism of one section to actuate the time delay relay of that section only when

40 the differential mechanism of the next succeeding section is not operated after actuation of the preceding mechanism within the time set on said time delay relay, a "go" signal, normally operative, in each section, a "stop" signal in each 45 section, and means controlled by the time delay relay in a section to extinguish the "go" signal and operate the "stop" signal in said section upon operation of the "stop" signal in any section.

23. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each section, means controlled by the actuation of a differential mechanism of one section to actuate the time delay relay of that section only when

50 the differential mechanism of the next succeeding section is not operated after actuation of the preceding mechanism within the time set on said time delay relay, a "go" signal, normally operative, in each section, a "stop" signal in each section, means controlled by the time delay relay in a section to extinguish the "go" signal and operate the "stop" signal in said section upon actuation of said time delay relay,

55 and means to extinguish the "go" signals and operate the "stop" signals of the preceding sections of the highway upon operation of the "stop" signal in any section.

60 24. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each section, means controlled by the actuation of a differential mechanism of one section to actuate the time delay relay of that section only when

65 the differential mechanism of the next succeeding section is not operated after actuation of the preceding mechanism within the time set on said time delay relay, a "go" signal, normally operative, in each section, a "stop" signal in each section, means controlled by the time delay relay in a section to extinguish the "go" signal and operate the "stop" signal in said section upon actuation of said time delay relay, means to extinguish the "go" signals and operate the "stop" signals of the preceding sections of the highway upon operation of the "stop" signal in any section, a remote control panel, signal means on said panel for each of said sections, the means controlled by said time delay relay of a section being adapted to actuate the signal means on said panel for said section, when the "go" sig-

nal in said section is extinguished and the "stop" signal operated.

23. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each section, means controlled by the actuation of a differential mechanism of one section to actuate the time delay relay of that section only when the differential mechanism of the next succeeding section is not operated after actuation of the preceding mechanism within the time set on said time delay relay, a "go" signal normally operative, in each section, a "stop" signal in each section, means controlled by the time delay relay in a section to extinguish the "go" signal and operate the "stop" signal in said section upon actuation of said time delay relay, a remote control panel, signal means on said panel for each of said sections, the means controlled by said time delay relay of a section being adapted to 25 actuate the signal means on said panel for said section, when the "go" signal in said section is extinguished and the "stop" signal operated.

24. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each of said sections, means controlled by the actuations of a differential mechanism of one section to actuate the time delay relay of that section, a second time delay relay for each of said sections, means to actuate the second time delay relay of a section upon actuation of its corresponding first time delay relay and of the succeeding section's differential mechanism before the time set on said first time delay relay, a "caution" signal for each section except the first section, and means to actuate the "caution" signal of a succeeding section upon actuation of the second time delay relay of a preceding section.

25. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each of said sections, means controlled by the actuations of a differential mechanism of one section to actuate the time delay relay of that section, a second time delay relay for each of said sections, means to actuate the second time delay relay of a section upon actuation of its corresponding first time delay relay and of the succeeding section's differential mechanism before the time set on said first time delay relay, a "caution" signal for each section except the first section, means to actuate the "caution" signal of a succeeding section upon actuation of the second time delay relay of a preceding section, a remote control panel, signal means on said panel for each section except the first section, and means to operate the panel signal means of a section upon actuation of the "caution" signal in said section.

26. In combination, a plurality of vehicle ac-

tuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each of said sections, means controlled by the differential mechanism of each section to actuate the time delay relay of said section, a second time delay relay for each of said sections, means to actuate each second time delay relay upon actuation of the corresponding first time delay relay and of the succeeding section's differential mechanism before the time set on said first time delay relay, a "caution" signal for each section except the first section, means to actuate the "caution" signal of a succeeding section upon actuation of the second time delay relay of a preceding section, a third time delay relay for each section, means controlled by the differential mechanism of one section to actuate the third time delay relay of that section only when the differential mechanism of the next succeeding section is not operated within the time set on said third time delay relay, a "go" signal, normally operative, in each section, a "stop" signal in each section, and means controlled by the third time delay relay of any section to extinguish the "go" signal of the same section and operate the "stop" signal in said section upon actuation of the third time delay relay of said section.

27. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each of said sections, means controlled by the differential mechanism of each section to actuate the time delay relay of said section, a second time delay relay for each of said sections, means to actuate each second time delay relay upon actuation of the corresponding first time delay relay and of the succeeding section's differential mechanism before the time set on said first time delay relay, a "caution" signal for each section except the first section, means to actuate the "caution" signal of a succeeding section upon actuation of the second time delay relay of a preceding section, a third time delay relay for each section, means controlled by the differential mechanism of one section to actuate the third time delay relay of that section only when the differential mechanism of the next succeeding section is not operated within the time set on said third time delay relay, a "go" signal, normally operative, in each section, a "stop" signal in each section, means controlled by the third time delay relay of any section to extinguish the "go" signal of the same section and operate the "stop" signal in said section upon actuation of the third time delay relay of said section, and means to extinguish the "go" signals and operate the "stop" signals of the preceding sections of the highway upon operation of the "stop" signal in any section.

28. In combination, a plurality of vehicle actuated means disposed at spaced intervals along the lane of a highway dividing the highway into a plurality of successive sections, a differential mechanism for each section controlled by the actuations of the vehicle actuated means bound-

ing said sections, to indicate the number of vehicles in said section, a time delay relay for each of said sections, means controlled by the differential mechanism of each section to actuate the time delay relay of said section, a second time delay relay for each of said sections, means to actuate each second time delay relay upon actuation of the corresponding first time delay relay and of the succeeding section's differential mechanism before the time set on said first time delay relay, a "caution" signal for each section except the first section, means to actuate the "caution" signal of a succeeding section upon actuation of the second time delay relay of a preceding section, a third time delay relay for each section, means controlled by the differential mechanism of one section to actuate the third time delay relay of that section only when the differential mechanism of the next succeeding section is not operated within the time set on said third time delay relay, a "go" signal, normally operative, in each section, a "stop" signal in each section, means controlled by the third time delay relay of any section to extinguish the "go" signal of the same section and operate the "stop" signal in said section upon actuation of the third time delay relay of said section, means to extinguish the "go" signals and operate the "stop" signals of the preceding sections of the highway upon operation of the "stop" signal in any section, a remote control panel, signal means on said panel for each of said sections, said means controlled by the third time delay relay of any section including means for actuating the signal means on said panel of said section, when the "go" signal in said section is extinguished and the "stop" signal of said section operated.

29. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each of said sections, means controlled by the differential mechanism of each section to actuate the time delay relay of said section, a second time delay relay for each of said sections, means to actuate each second time delay relay upon actuation of the corresponding first time delay relay and of the succeeding section's differential mechanism before the time set on said first time delay relay, a "caution" signal for each section except the first section, means to actuate the "caution" signal of a succeeding section upon actuation of the second time delay relay of a preceding section, a third time delay relay for each section, means controlled by the differential mechanism of one section to actuate the third time delay relay of that section only when the differential mechanism of the next succeeding section is not operated within the time set on said third time delay relay, a "go" signal, normally operative, in each section, a "stop" signal in each section, means controlled by the third time delay relay of any section to extinguish the "go" signal of the same section and operate the "stop" signal in said section upon actuation of the third time delay relay of said section, means to extinguish the "go" signals and operate the "stop" signals of the preceding sections of the highway upon operation of the "stop" signal in any section, a remote control panel, signal means

on said panel for each of said sections, said means controlled by the third time delay relay of any section including means for actuating the signal means on said panel of said section, when the "go" signal in said section is extinguished and the "stop" signal of said section operated, a second signal means on said panel for each section except the first section, and means to operate said second panel signal means of a section upon actuation of the "caution" signal in said section.

30. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each of said sections, means controlled by the differential mechanism of each section to actuate the time delay relay of said section, a second time delay relay for each of said sections, means to actuate each second time delay relay upon actuation of the corresponding first time delay relay and of the succeeding section's differential mechanism before the time set on said first time delay relay, a "caution" signal for each section except the first section, means to actuate the "caution" signal of a succeeding section upon actuation of the second time delay relay of a preceding section, a third time delay relay for each section, means controlled by the differential mechanism of one section to actuate the third time delay relay of that section only when the differential mechanism of the next succeeding section is not operated within the time set on said third time delay relay, a "go" signal, normally operative, in each section, a "stop" signal in each section, means controlled by the third time delay relay of any section to extinguish the "go" signal of the same section and operate the "stop" signal in said section upon actuation of the third time delay relay of said section, a remote control panel, signal means on said panel for each of said sections, said means controlled by the third time delay relay of any section including means for actuating the signal means on said panel of said section, when the "go" signal in said section is extinguished and the "stop" signal of said section operated.

31. In combination, a plurality of vehicle actuated means disposed at spaced intervals along the lane of a highway dividing the highway into a plurality of successive sections, a differential mechanism for each section controlled by the actuations of the vehicle actuated means bounding said sections, to indicate the number of vehicles in said section, a time delay relay for each of said sections, means controlled by the differential mechanism of each section to actuate the time delay relay of said section, a second time delay relay for each of said sections, means to actuate each second time delay relay upon actuation of the corresponding first time delay relay and of the succeeding section's differential mechanism before the time set on said first time delay relay, a "caution" signal for each section except the first section, means to actuate the "caution" signal of a succeeding section upon actuation of the second time delay relay of a preceding section, a third time delay relay for each section, means controlled by the differential mechanism of one section to actuate the third time delay relay of that section only when the

differential mechanism of the next succeeding section is not operated within the time set on said third time delay relay, a "go" signal, normally operative, in each section, a "stop" signal in each section, means controlled by the third time delay relay of any section to extinguish the "go" signal of the same section and operate the "stop" signal in said section upon actuation of the third time delay relay of said section, a remote control panel, signal means on said panel for each of said sections, said means controlled by the third time delay relay of any section including means for actuating the signal means on said panel of said section, when the "go" signal in said section is extinguished and the "stop" signal of said section operated, a second signal means on said panel for each section except the first section and means to operate said second panel signal means of a section upon actuation of the "caution" signal in said section.

32. In combination, a plurality of vehicle actuated means disposed at spaced intervals along the lane of a highway dividing the lane into a plurality of successive sections, a "go" signal, normally operative, for each section, a "stop" signal for each section, an electrical circuit interconnecting said vehicle actuating means and said signals, said circuit including a delayed time relay for each section, means controlled by the vehicle actuated means at the entrance of a section to actuate the time delay relay of said section when the vehicle actuated means at the exit of said section is not actuated after actuation of the entrance means within the time set on said time delay relay, and means controlled by said time delay relay to extinguish the "go" signal of said section and operate said "stop" signal upon actuation of said time delay relay.

33. In combination, a plurality of vehicle actuated means disposed at spaced intervals along the lane of a highway dividing the lane into a plurality of successive sections, a "go" signal, normally operative, for each section, a "stop" signal for each section, an electrical circuit interconnecting said vehicle actuating means and said signals, said circuit including a delayed time relay for each section, means controlled by the vehicle actuated means at the entrance of a section to actuate the time delay relay of said section when the vehicle actuated means at the exit of said section is not actuated after actuation of the entrance means within the time set on said time delay relay, means controlled by said time delay relay to extinguish the "go" signal of said section and operate said "stop" signal upon actuation of said time delay relay, and means to extinguish the "go" signals and operate the "stop" signals of the preceding sections of the highway upon operation of the "stop" signal in any section.

34. In combination, a plurality of vehicle actuated means disposed at spaced intervals along the lane of a highway dividing the lane into a plurality of successive sections, a "go" signal, normally operative, for each section, a "stop" signal for each section, an electrical circuit in-

terconnecting said vehicle actuating means and said signals, said circuit including a delayed time relay for each section, means controlled by the vehicle actuated means at the entrance of a section to actuate the time delay relay of said section when the vehicle actuated means at the exit of said section is not actuated after actuation of the entrance means within the time set on said time delay relay, means controlled by said time delay relay to extinguish the "go" signal of said section and operate said "stop" signal upon actuation of said time delay relay, and means to extinguish the "go" signals and operate the "stop" signals of the preceding sections of the highway upon operation of the "stop" signal in any section, a remote control panel, signal means on said panel for each of said sections, the means controlled by said time delay relay including means for actuating said signal means on said panel of one section, when the "go" signal in said section is extinguished and the "stop" signal of said section operated.

35. In combination, a plurality of vehicle actuated means disposed at spaced intervals along the lane of a highway dividing the highway into a plurality of successive sections, a time delay relay for each section, means controlled by the actuation of the vehicle actuated means at the entrance of each section to actuate the time delay relay of said section, a second time delay relay for each section, means to actuate the second time delay relay of a section upon actuation of the first time delay relay of said section and of the vehicle actuated means located at the exit of a section after actuation of the entrance means before the time set on said first time delay relay, a "caution" signal for each section except the first section, and means to actuate the "caution" signal of a succeeding section upon actuation of the second time delay relay of a preceding section.

36. In combination, a plurality of vehicle actuated means disposed at spaced intervals along the lane of a highway dividing the highway into a plurality of successive sections, a time delay relay for each section, means controlled by the actuation of the vehicle actuated means at the entrance of each section to actuate the time delay relay of said section, a second time delay relay for each section, means to actuate the second time delay relay of a section upon actuation of the first time delay relay of said section and of the vehicle actuated means located at the exit of a section after actuation of the entrance means before the time set on said first time delay relay, a "caution" signal for each section except the first section, means to actuate the "caution" signal of a succeeding section upon actuation of the second time delay relay of a preceding section, a remote control panel, signal means on said panel for each section except the first section, and means to operate the panel signal means of a section upon actuation of the "caution" signal in said section.

BENJAMIN COOPER.
